BLADE DISPENSING AND RECEIVING
MAGAZINEVincent R. Bailey, Chestnut Hill, Mass., assignor
to The Gillette Company, a corporation of
Delaware

Application August 13, 1948, Serial No. 43,977

8 Claims. (Cl. 206—16)

1

This invention relates to a razor blade magazine which is designed to receive and dispense a stack of unwrapped double-edged razor blades, and especially to provide for novel blade transfer movements by means of which a used blade in a razor may be removed and a fresh blade from the stack in the magazine may be inserted in place of the blade which is removed. In a preferred embodiment the invention is exemplified by a mechanism for removal and disposal of used blades simultaneously with installation of a new blade in a razor having opposed cooperating blade-clamping members although the invention is not intended to be limited to any particular type of blade-holding device.

It is in general an object of the invention to improve methods of dispensing and handling unwrapped double-edged razor blades, having reference both to the removal of a used blade from a razor and the insertion of a fresh blade to take the place of the used blade. Another object is to provide a safe, efficient means of transferring blades from a stacked position in a merchandising unit into a guided dispensing position which is especially adapted to facilitate register or actual engagement of each blade with the blade-holding portions of a razor for which the blades are intended. It is a further object of the invention to provide means for a two-way blade transfer in which a used blade is not only removed and replaced by a fresh blade but the old blade is also deposited in a used blade bin, all in one continuous interrelated operation during which the hands of the user are protected from contact with the sharp cutting edges of the blades at all times.

The blade handling method and mechanism of the invention furnish one desirable way of accomplishing the foregoing objectives by introducing a novel cycle of blade handling movements, and by combining a used blade bin with a unique blade magazine case and a reciprocating slide member which is arranged to move into positions of register with both the bin and the case. The magazine case is so constructed that it may receive and resiliently support a stack of blades piled one upon another in alternately and oppositely overlapped relation.

Advantage is taken of such a blade alternation to support some of the blades at their end portions in a flexed or bent over position as a result of which the entire stack of blades is fanned out to present free ends lying in spaced-apart relation in a position where they may be conveniently and positively engaged by the slide member.

2

The cycle of blade handling movements starts with selective removal of an uppermost blade from the stack while in the fanned out or flexed position described. The separated blade is next carried forwardly and transferred from the magazine case to a razor. As the newly issued blade takes its place in the razor, the used blade is simultaneously displaced and engaged by the blade handling slide which retracts the used blade. The cycle is completed by the used blade being drawn rearwardly and deposited in a used blade bin.

Another desirable feature of the invention therefore is the combination with a blade magazine of a used blade bin superimposed upon the magazine in a position to provide a slide guideway which extends between the magazine and the bin. Still another feature of the invention is the provision of a blade retracting element 20 on a slide member and blade passageways located in the path of movement of the slide to facilitate a two-way transfer of blades during each cycle of movement of the slide.

These and other objects and novel features will be more fully understood and appreciated from the following description of a preferred embodiment of the invention selected for purposes of illustration and shown in the accompanying drawings, in which

Fig. 1 is a perspective view illustrating the improved blade dispensing magazine of the invention;

Fig. 2 is an end elevational view of one type of razor with which the magazine shown in Fig. 1 is designed to be employed;

Fig. 3 is a side elevational view further illustrating the razor and magazine member in separated relation;

Fig. 4 is a sectional view taken on the line 4—4 of Fig. 8;

Fig. 5 is a plan view taken on the line 5—5 of Fig. 3 and illustrating the blade magazine partly engaged on over the razor;

Fig. 6 is a vertical cross-sectional view;

Fig. 7 is another vertical cross section taken on the line 7—7 of Fig. 6;

Fig. 8 is a detail plan view of a slide member;

Fig. 9 is a vertical cross-sectional view showing another step in the transfer of a blade into the razor;

Fig. 10 is a vertical cross-sectional view taken at a point when the new blade has been inserted in the razor and the slide is about to start its return movement;

Fig. 11 is another vertical cross-sectional view

3

showing the used blade partly removed and entering the blade bin;

Figs. 12 and 13 are sectional views showing the further positions assumed by the used blade of Fig. 11 as it is drawn rearwardly away from the razor;

Fig. 14 illustrates location of the used blade in its final position of rest in the blade bin; and

Fig. 15 is a detail view of a spring member.

It is contemplated that the blade magazine of the invention will be used primarily in merchandising a limited number of blades and although not limited to any specific number, is especially suited to containing and dispensing a stack of at least ten blades of the double-edged type noted above. The magazine is further intended to constitute in general a simple, convenient dispensing unit by means of which a blade may, if desired, be selectively detached from a stack of blades and moved out of the magazine into a position where the blade may be grasped by the fingers or directly hooked over the blade-holding projections of a razor blade holder. It is also intended however that the magazine may be employed as a translating member to provide for a guided dispensing or blade locating operation in which the blade is fully inserted in the safety razor so that there remains only the operation of tightening the head of the razor before using.

As an aid to more fully visualizing the blade handling cycle, I have illustrated in several figures of the drawing the principal parts of a commercial type razor. These razor parts include a cylindrical handle 2 (Fig. 3), at the upper end of which is solidly fixed a lower blade support 4. An upper blade support 6 is resiliently clipped to the member 4 by a U-shaped extension 8 which engages against the under side of member 4 and is normally held in a raised position by means of spring members 10 (Figs. 2 and 3). Slidably received in the handle 2 is a threaded rod 12 which is spring held so that it may be forced upwardly to project above the blade support 4 into a position in which its threaded extremity may be screwed into threaded portions 14 of the upper blade support or cap 6.

In the conventional method of installing a blade in the razor structure described, a reduced end of a blade is inserted between the members 4 and 6 and advanced over a ramp 16 which is formed with a centrally disposed guide rib 18 for alining the blade in a proper relative position. When thus located the blade is resiliently gripped by the spring 10 and held in an intermediate position until the threaded member is forced upwardly through the median slot in the blade and screwed into the upper blade support 6.

In accordance with the invention I provide a cycle of blade handling movements and a suitable mechanism designed for operation with the above described razor assembly while it is in the intermediate position referred to, with the upper blade support 6 occurring in a raised position, thus presenting at one end of the razor a blade transferring passageway along the ramp 16.

The more essential parts of the blade dispensing magazine of the invention include a magazine case; blade gripping and alining mechanism for supporting blades in a firm position in the case; a used blade bin or receptacle superimposed upon the case; and a feed slide member equipped with blade advancing and blade retracting elements. An essential provision in the

4

general organization of these parts is means for protecting the blades and maintaining the double cutting edges of these elements in a shielded position at all times during their storage and movement out of the magazine when a blade dispensing cycle is carried out. This protection is achieved by employing a casing whose width is substantially greater than the width of any one of the blades so that the cutting edges at all times may lie in spaced relation to the two opposite inner surfaces of the casing. Additional protection is furnished by the blade gripper mechanism which helps to align the blades and maintain them under positive engagement from two opposite sides so that lateral displacement is avoided at all times up until a blade leaves the magazine.

Thus in the embodiment of the invention shown in the drawings, numeral 20 denotes the magazine case which is rectangular in shape and of appreciably greater width than the width of the blades it is to contain. The case may be made of various materials such as metal, plastic, paper and the like, and is adapted to receive a stack of blades of the slotted, double edge type as has been suggested in Fig. 1. As indicated therein the case is formed with a closed rear end and an open front end to provide a blade dispensing aperture 22.

At its upper side the case is constructed with transverse inturned flanges 24 and 26 which are spaced apart to provide a slideway in which there is slidably supported a reciprocating slide member 28. Mounted upon the transverse flanges is a used blade receptacle or bin 29 which is constructed with recessed under edges 30 spaced above the transverse flanges 24 and 26 to define a passageway for the slide and yet maintain the slide firmly against the case.

As suggested in Figs. 6 and 7, slide 28 preferably consists of a flat strip of relatively rigid material designed to extend across the transverse flanges 24 and 26 and shaped with a depressed central body portion which is snugly fitted between the flanges referred to in a manner such that these flanges constitute a guideway for maintaining the slide in a constantly aligned position as it is moved back and forth along the case. The extremities of the slideway extend from either side of the case as noted in Figs. 1 and 6 and may also be formed with serrated or knurled surfaces to facilitate gripping the slide for example between the thumb and forefinger.

At its under side the slide is formed with a blade advancing element 32 consisting of a hook-like member projecting forwardly in a plane somewhat below the top of the slide. Located on the under surface of slide 28 at either side of the blade advancing element 32 is a pair of cams 34 and 36. Each cam is constructed with front and rear beveled faces which meet to form V edges extending transversely with respect to the case. The front beveled surfaces on the cams extend upwardly above the level of the blade advancing element 32 and cooperate with the blade advancing element 32 to define a blade entranceway.

The arrangement of the cams relative to element 32 is chosen so that the reduced end of a razor blade projecting up into the path of movement of the slide will first make contact with the front beveled surfaces of cams 34 and 36. The effect of the cams is to flex the blade end downwardly until it engages the shank of the blade advancing element 32.

5

The slide is further constructed with a blade depressing element 38 mounted centrally at the top of the slide body and projecting forwardly and downwardly as illustrated in Figs. 4 and 6 to terminate in a turned up tip 40. At the upper side of the blade depressing element 38 and located intermediate the tip 40 and the point of meeting of element 38 with the body of the slide is a blade retracting hook 42 which extends rearwardly in a plane well above the body portion of the slide.

It is pointed out that the centrally located position of the blade depressing element 38 as well as the retracting element 42 provides for these elements being arranged in register with the median slot of an uppermost blade 44 as suggested in Fig. 4 of the drawings. In this way provision is made for the blade depressing element 38 being passed downwardly through the slot of the uppermost blade into contact with an immediately underlying blade as will be made clearer from a detailed discussion of the stacked blade arrangement appearing hereinafter. It should also be observed that since the blade retracting element 42 is secured to the top side of the blade depressing element 38, it continues to remain well above the level of the slide even though the depressing element extends downwardly to a considerable extent.

The arrangement and operation of the slide 28 may be better appreciated from a consideration of the unique blade assembly provided in the case 20. As noted in the drawings, a stack of blades is mounted in the case with the constituent blades of the stack being supported upon one another in alternately and oppositely overlapped or staggered relation to provide a series of projecting blade ends at either side of the stack. Those blades whose ends lie nearest to the blade dispensing aperture 22 are conveniently referred to as front blades while the remaining blades are referred to as rear blades. The forward ends of the front blades when thus located all extend well beyond corresponding ends of the rear blades in spaced relation and can be forced together an appreciable distance because the solid end portions of the rear blades act as fulcrums when the projecting ends of the front blade are forced together as shown in Fig. 6. This has the effect of springing opposite ends of the blades apart in a fanned out position. I have provided suitable mechanism for forcing together the front blade ends while maintaining all of the blades in a correctly aligned position. Included in this mechanism are two guide posts 46 and 48, a curved slotted spring 50 and two spaced-apart bar cams 52 and 54 extending downwardly from the under sides of the transverse edges 24 and 26 and having upwardly and inwardly inclined blade-positioning faces. The posts are mounted centrally in the case in longitudinally spaced relation to register with a circular opening 58 and a diamond shaped opening 56 in each blade. Since there are two diamond shaped openings and an intermediate circular opening in each blade, convenient blade alternation is readily achieved by placing the front blades in a position such that the circular opening 58 receives therethrough post 46 while alternate rear blades are placed in a position such that circular opening 56 receives therethrough post 48. The posts are further formed with upper inclined surfaces 60 and 62 which are designed to permit a flexed razor blade and to be drawn forwardly up over the top of the post in

6

response to movement of the slide member when engaged with the blade. The tops of the posts are also provided with slots 80 and 82 extending longitudinally of the magazine.

5 The spring 50 is interposed between the stack of blades and the bottom of the case at the outer end of the stack and is curved upwardly to resiliently urge the projecting ends of front blades in an upward direction. Throughout a part of 10 its length the spring has intermediate body portions removed to form spaced-apart ends straddling the two posts and bearing against the lowest blade of the stack along two sides.

The two cams 52 and 54 extend downwardly 15 at an inclination from the under side of the transverse flanges at either side of the magazine case in a position to cooperate with the spring 50 and force the front blade ends together as shown in Fig. 6 and to support the uppermost blade unflexed in upwardly and rearwardly inclined position. Each cam has two beveled surfaces meeting to form V edges as illustrated. These V edges not only aid in forcing the blade ends together but also insure that the end of the uppermost blade as it leaves the blade dispensing aperture 22 will be at the correct level for registering with the blade receiving aperture of the razor into which the blade is to be inserted.

Located just ahead of the spring 50 and cams 30 52 and 54 in the bottom of the case 20 is a stop member in the form of a transverse wall 64 which projects upwardly a distance sufficient to hold the spring 50 in a correct position. The case is further constructed with an extension 66 which 35 is formed with guide edges 68 adapted to engage and slide over the blade supporting member 4 of the razor in the manner indicated in Fig. 6, with the stop 64 lying snugly against the end of member 4. When the case and razor are 40 placed in interlocking relation as indicated in Fig. 6, it will be noted that the V edges of cams 52 and 54 under which blades must slide as they are ejected occur in a horizontal plane which intersects the ramp 16 of the razor, thus insuring 45 that the end of a blade leaving the magazine will strike against the ramp at a point about half way up its inclined surface.

It should also be observed that the thickness of the magazine case considered vertically is 50 chosen such at that the upper blade holding member 6 in the raised position shown in the drawings will be above the transverse edges 24 and 26 of the case when the razor and case are in interlocked relation. This arrangement permits a used blade in the razor, such as for example the used blade 69 shown in Fig. 6, to be forced upwardly against the upper blade holding member 6 in which position the blade end may be withdrawn and passed up over the transverse edges 24—26 into a used blade entrance-way 70. The top of the entranceway 70 is formed by two edges 72 and 74 integral with the used blade bin 29 and these edges occur at a height suitable for guiding the used blade end 65 against a curved spring 76 supported longitudinally in the used blade bin as noted in Fig. 6.

The structure and elements described are made use of to secure blades in various positions in the magazine case as well as the razor in carrying out a blade holding cycle of the character already described. The several positions and movements will now be described beginning with a description of the blade assembly in the magazine case at the commencement of a blade dispensing cycle, it being assumed that the maga-

zine has been attached to a razor already containing a blade 69 which is to be discarded as suggested in Fig. 6.

Starting with a fully loaded magazine, the uppermost blade in the stack will preferably consist of a rear blade which in Fig. 6 is exemplified by the blade 44. The circular opening 58 of this blade has received therethrough the post 48. The end of blade 44 nearest to the blade aperture 22 is resiliently gripped between the immediately underlying blade in the stack and the beveled surfaces of the cams 52 and 54. The opposite end of blade 44 extends rearwardly and upwardly in a slightly flexed position and rests against the under side of the transverse flanges 24 and 26. The remaining blades extend into free space in the magazine and fan up and down in that portion of it.

As shown in Fig. 6 the slide 28 is in its extreme right hand position in which location the depresser element is engaged through the median slot of blade 44 with its turned up tip 40 bearing against the reduced end of the next underlying blade 78 in the stack, thus maintaining this end of the blade in a depressed spaced position below blade 44 and engaged about the posts 46 and 48.

As the slide 28 is moved forwardly or in a direction from right to left as viewed in Fig. 6, the beveled forward surfaces of cams 34 and 36 begin to depress blade 44 and cause it to pass into engagement with the blade advancing element 32, there being ample opportunity for the latter member to extend underneath the end of blade 44 by reason of its overlapping disposition in the stack.

As soon as the blade advancing element 32 makes contact with blade 44 it begins to slide the blade forwardly, forcing its front end between the cams 52 and 54 and the remaining blades in the stack. It will be apparent that blade 78 and all underlying blades will be held in a fixed aligned position by reason of the engagement with the posts and by reason of the fact that the tip 40 of depresser 38 is guided in slots 80 and 82 in the tops of posts 46 and 48 so that blade 78 cannot spring up over the tops of posts 46 and 48.

Movement of the blade advancing element 32 beneath blade 44 with this blade in an inclined position results in the hooked extremity of element 32 passing through the median slot of the blade in which position member 32 maintains separation of blade 44 from blade 78 without further mechanical handling.

After a short travel the front end of blade 44 passes out of the blade aperture 22, being held at a predetermined level by the inclined faces of the cams 52 and 54, and moves ahead into contact with the ramp 16 of the razor and just below the nearer end of the used blade 69 as will be apparent from an inspection of Fig. 6.

Further passage of blade 44 causes the used blade 69 to be forced upwardly away from the ramp with the front end of blade 44 being substituted in its place in engagement with the guide rib 18 as noted in Fig. 9. Displacement of blade 69 continues against the action of spring 10 until blade 44 is completely seated in the blade supporting member 44 as illustrated in Fig. 10.

At this point in the blade handling cycle (Fig. 10) it will be seen that forward movement of the slide 28 is terminated and in this position the blade depressing element extends freely through the median slot of used blade 69 while

the blade retracting element 42 has also passed through the median slot of blade 69 and assumed a position such that it occurs at a level slightly above the reduced end of blade 69 in readiness to engage therewith as suggested in Fig. 10. The slide is then drawn rearwardly, retracting the blade 69 and guiding its end so that this end passes up over the transverse flanges 24 and 26 of the magazine and into the blade entranceway 10 leading to the used blade bin 29 as noted in Fig. 11. Continued movement of blade 69 rearwardly brings the blade against the extremity of curved spring 76 over which the blade is drawn with the spring becoming flattened out as indicated in Fig. 12. It should be understood at this point that spring 76 is of a generally forked or U-shaped formation as shown in Fig. 15 so that although the used blade 69 may be drawn up over the spring, the retracting element 42 actually moves in the slotted portion of the spring and remains in engagement with the reduced end of blade 69 up until it reaches an extreme position of rest at the right hand side of the case as viewed in Fig. 13. At this point the opposite end of blade 69 has been forced upwardly against the top of the blade bin. Upon the slide 28 beginning a new cycle the retracting element 42 is drawn ahead, releasing the end of blade 69 which then springs upwardly into a fully elevated position as shown in Fig. 14.

Having thus disclosed my invention and described in detail illustrative embodiments thereof, I claim as new and desire to secure by Letters Patent:

35. 1. In a razor blade magazine the combination of a case having a blade dispensing aperture, a slide movably secured in the case, a stack of blades mounted flatwise in the case in overlapping and staggered relation, cam elements 40 fixed in the case, the cam elements extending downwardly into contact with the uppermost blade in the stack, and a curved spring cooperating with the cam elements resiliently to deflect into engagement the outer ends of the blades 45 projecting at one end of the stack and thus hold blades in fulcrumed relation to one another, the inner ends of the blades thereby being spaced apart from one another and the uppermost blade 50 in the stack extending into the path of movement of the slide.

2. A blade magazine comprising in combination a case having a blade-dispensing opening at one end, a slide arranged to move along one side of the case, a stack of blades superimposed one 55 upon another in alternately and oppositely overlapping relation, opposed members for flatwise gripping the ends of those blades that project at one end of the stack to provide free blade extremities which lie in spaced-apart relation to one another at the other end of the stack, and a blade-advancing element located on the slide in a position to engage with the free end of the uppermost blade in the stack.

3. A magazine for longitudinally slotted razor 65 blades, comprising a rectangular enclosure having a blade exit opening at one end, a stack of flexible blades arranged in the enclosure being in alternately longitudinal staggered relation, a spring located beneath the blade stack adjacent to the exit opening, and an oppositely disposed upwardly and inwardly inclined cam cooperating with the spring to press together the ends of the blades projecting at that end of the stack and to fan out the opposite end of the uppermost blade of the stack against the

inclined cam, and a feed slide movable along one side of the enclosure in a path engaging the said fanned-out blade end.

4. A razor blade magazine comprising a case having an exit opening adjacent one end thereof, a stack of flexible slotted blades arranged alternately in longitudinally staggered relation in the case with solid end portions of alternate blades superposed at the outer ends of the stack, inwardly and upwardly sloping cam means fixed in the case and located above the stack, and an opposed spring located in the case below the stack and adjacent the exit opening causing the solid end portions at one end of the stack to contract and the uppermost blade of the stack to fan upwardly in unflexed condition against the sloping cam, and a feed slide movable in the case contacting the fanned end of the uppermost blade.

5. A razor blade magazine as defined in claim 4 in which the inner end of the blade stack projects into free space in the case and the blades fan upwardly and downwardly in that end of the stack.

6. A blade magazine as defined in claim 4 wherein said cam means includes a pair of spaced parallel overhead cams each having at its outer end a steeply inclined inwardly and downwardly sloping face disposed in divergent relation to an elongated inwardly and upwardly inclined blade-locating face.

7. A blade magazine comprising an elongated casing having an exit opening adjacent one end, spaced upstanding studs in the casing, a stack of flexible slotted blades held in alternate longitudinally staggered relation by said studs, an

underlying spring in the casing engaging the blade stack near the end thereof adjacent the exit opening, overhead means in the casing cooperating with said spring to cause the uppermost blade of the stack to fan away from the stack unflexed in an inwardly and upwardly inclined position, and a feed slide movable in the casing for contacting the inner end of said inclined blade to move the same through the exit opening.

8. A blade magazine as defined in claim 7 in which the feed slide has a pair of spaced downwardly and rearwardly inclined cams, and a cooperating forwardly extending arm having a vertical blade-advancing portion located near the base of the cams in position for engaging the end of the uppermost blade flexed downwardly by the cams as the slide is advanced.
